Primary Examiner — Deanna L Pratt(74) *Attorney, Agent, or Firm* — Finnegan, Henderson, Farabow, Garrett & Dunner, LLP(57) **CLAIM**

The ornamental design for a communications device, as shown and described.

DESCRIPTION

FIG. 1 is a front, top, right perspective view of a communications device, showing the new design;

FIG. 2 is a rear, top, left perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom view thereof.

The broken lines of even length shown in the drawings illustrate portions of the communications device that form no part of the claimed design. Contrast in appearance is shown using line shading on some surfaces and stippling shading on others.
